MERCERIZING AGENT

Robert L. Sibley, Nitro, W. Va., assignor to Monsanto Chemical Company, St. Louis, Mo., a corporation of Delaware

No Drawing. Application May 20, 1939,
Serial No. 274,788

8 Claims. (Cl. 8—127)

The present invention relates to a new and improved process and composition for improving and accelerating the wetting properties of alkaline aqueous media, such as strong alkaline solutions used for mercerizing cellulosic fibers. It is known that ordinary soaps, namely, the alkali metal salts of high molecular weight fatty acids, possess wetting properties in distilled water. In strong alkaline solutions, however, such compounds have very little or no wetting properties.

An object of this invention is to produce alkaline aqueous media for improving and accelerating the mercerizing effect of alkalies upon cellulosic fibers such as cotton and similar textile materials. A further object of the invention is to produce an aqueous bath which is relatively concentrated in alkaline reacting substances, such as caustic, and yet possesses marked wetting, penetrating and dispersing characteristics. A specific object of the invention is to produce relatively concentrated solutions of alkali metal hydroxides which possess the property of accelerating the mercerizing effect of strong alkaline hydroxides upon cellulosic fibers.

The objects of the invention are accomplished by adding to strongly alkaline aqueous media a particular type of wetting agent comprising soluble N-alkylated aromatic amine di-sulfonates. Also the soluble salt, preferably the alkali metal salt such as the sodium and potassium salts, may be formed in the mercerizing media by adding thereto the N-alkylated aromatic amine di-sulfonic acids. I have found that these di-sulfonates possess excellent wetting properties in the presence of strong alkalies, such as used in mercerizing baths.

The di-sulfonates employed in the present invention may be represented by the following general formula:

wherein R represents an aromatic nucleus of the benzene, biphenyl and naphthalene type; R₁ represents a hydrogen or an alkyl radical containing from two to six carbon atoms; Me represents an alkali metal such as sodium or potassium; and "alkyl" represents an alkyl radical containing from two to six carbon atoms. Illustrative examples of these compounds are as follows:

N-ethyl aniline di-sodium-sulfonate
N-n-propyl aniline di-sodium-sulfonate
N-isopropyl aniline di-sodium-sulfonate
N-n-butyl aniline di-sodium-sulfonate

- N-tertiarybutyl aniline di-sodium-sulfonate
- N-isobutyl aniline di-sodium-sulfonate
- N-amyl aniline di-sodium-sulfonate
- N-n-dibutyl aniline di-sodium-sulfonate
- 5 N-n-dibutyl aminotoluene di-sodium-sulfonate
- N-tertiaryamyl p-amino-biphenyl di-sodium-sulfonate
- N-n-propyl p-amino-biphenyl di-sodium-sulfonate
- 10 N-n-propyl o-amino-biphenyl di-sodium-sulfonate
- N-isopropyl o-amino-biphenyl di-sodium-sulfonate
- N-n-butyl o-amino-biphenyl di-sodium-sulfonate
- 15 N-tertiary butyl o-amino-biphenyl di-sodium-sulfonate
- N-isobutyl o-amino-biphenyl di-sodium-sulfonate
- N-n-amyl o-amino-biphenyl di-sodium-sulfonate
- 20 N-tertiaryamyl o-amino-biphenyl di-sodium-sulfonate
- N-hexyl o-amino-biphenyl di-sodium-sulfonate
- N-n-butyl naphthylamine di-sodium-sulfonate
- N-n-amyl naphthylamine di-sodium-sulfonate
- 25 N-tertiaryamyl naphthylamine di-sodium-sulfonate

Mixtures of the above products may be used, for example, N-amyl and N-diamyl o-amino biphenyl di-sodium-sulfonates, and N-n-butyl and N-n-dibutyl o-amino biphenyl di-sodium-sulfonates, as well as mixtures of the other N-alkyl and N-di-alkyl aromatic amine di-alkalimetal-sulfonates.

Within the classes of compounds herein disclosed, the group of N-alkylated o-amino-biphenyl di-sodium sulfonates is extremely effective for use in mercerizing baths and their superior effectiveness in this respect is unique.

The following examples illustrate some of the methods that may be used to prepare the herein described N-alkylated aromatic amine di-sulfonic acids and their salts.

EXAMPLE I

- 45 Five tenths mols of ortho-amino biphenyl, 150 grams of butyl alcohol (solvent) and 0.5 mol of n-butyl bromide were refluxed for four hours at about 117° C. and the reaction mixture was then heated to distill off the solvent. The residue was washed with 25% aqueous caustic solution to liberate the free base and then distilled under reduced pressure to recover the N-alkylated amino biphenyls. Forty-two and a half grams of N-n-butyl ortho-amino biphenyl was distilled from the 50 reaction mixture at a temperature of 128—135° C.

at 2 mm. pressure and 51.6 grams of N-n-dibutyl ortho-amino biphenyl distilled at 135-160° C. at 2 mm. pressure. Either of these N-alkyl o-amino-biphenyls or the mixture may be sulfonated by the following method.

Twelve grams of the N-dibutyl ortho-amino diphenyl, 50 grams of dry carbon tetrachloride (solvent) and 11.5 grams of chlorosulfonic acid were refluxed together at 75-80° C. until the last trace of HCl was liberated. The reaction mixture was diluted with water and the carbon tetrachloride removed. The water solution was then dried on steam plates to a white powder. By neutralizing the acid with sodium hydroxide, the N-n-dibutyl-ortho-amino-biphenyl di-sodium-sulfonate is obtained.

EXAMPLE II

One mol of ortho-amino biphenyl hydrochloride, three mols of tertiary amyl alcohol and one gram of iodine (catalyst) were heated in a rotary autoclave for five hours at 175-180° C. under 450 to 480 pounds pressure. The reaction product was then made alkaline with sodium hydroxide, filtered and washed with water until neutral. The reaction products were then distilled under reduced pressure and the N-tertiary-amyl-ortho-amino biphenyl distilled over between 140-150° C. at one mm. pressure.

One mol of a N-tertiary-amyl-ortho-amino-biphenyl, two mols of chlorosulfonic acid and 1,000 grams of carbon tetrachloride were refluxed for five hours. The carbon tetrachloride (solvent) was separated off and the reaction product dissolved in alcohol and neutralized with 420 c. c. of 25% aqueous sodium hydroxide. The neutralized alcoholic solution was filtered and then dried. The N-tertiary-amyl-ortho-amino biphenyl di-sulfonic acid, in particularly quantitative yield, was recovered by evaporating the alcohol therefrom. Upon neutralization of the acid with caustic or sodium carbonate, the corresponding di-sulfonate is obtained.

EXAMPLE III

One mol of ortho-amino-diphenyl hydrochloride, three mols of tertiary butyl alcohol, and one gram of iodine (catalyst) were heated in a rotary autoclave for five hours at 125-135° C. under 600 to 700 pounds pressure. The reaction product was then made alkaline with sodium hydroxide, filtered, and washed with water until neutral. Benzene was then added to dissolve the reaction product from the remainder of the reacted constituents. The benzene solution was distilled to remove the benzene and the residue was distilled under reduced pressure. The N-tertiary butyl ortho-amino biphenyl distilled between 135-140° C. at 1 mm. pressure.

One-tenth mol of the N-tertiary butyl ortho-amino biphenyl, 0.2 mol of chlorosulfonic acid and 100 grams of carbon tetrachloride (solvent) were mixed together at about 20-30° C. and refluxed for five hours. The carbon tetrachloride was separated off and the reaction product dissolved in alcohol and neutralized with 36 c. c. of 25% aqueous sodium hydroxide. After cooling the neutralized solution, it was filtered and the alcoholic solution dried. The N-tertiary butyl-ortho-amino biphenyl di-sulfonic-acid was recovered therefrom by evaporating the alcohol. Upon neutralization of the acid with an alkali, the corresponding di-sulfonate is obtained.

EXAMPLE IV

Di-n-butyl aniline was sulfonated by the pro-

cedure used in the preceding example to prepare the di-n-butyl aniline di-sodium-sulfonate.

In general, the N-alkylated aromatic amine may be prepared by reacting the hydrochloride of the aromatic amine with the various alcohols under a pressure of 400 to 600 pounds at a temperature of about 150-210° C. If desired, a small amount of iodine may be used to catalyze the reaction. After neutralizing the charge, the excess unreacted alcohol is recovered by distillation and the unreacted amine as well as the N-alkylated amine are separated by fractional distillation under reduced pressure. The sulfonation is preferably carried out in a solvent such as carbon tetrachloride or tetrachlor-ethane, and two mols of chlorosulfonic acid is used for each mol of the N-alkylated aromatic amine.

As pointed out hereinbefore, the salts of disulfonated N-alkylated aromatic amines are particularly adapted for use in mercerizing baths because they retain their wetting properties in the presence of strong alkaline solutions. In general, these sulfonated products are used in concentrations ranging from 0.2% to 3% but preferably concentrations within the 0.8% to 1.5% are used. The concentration or alkali, such as sodium hydroxide, in the mercerizing bath may vary over the range commercially used for mercerizing cotton fabrics. In general the alkali content of the bath will vary from 12 to 40%. The herein described di-sulfonated compounds may be added to the bath in the form of the salt but if desired they may be added in the form of the free acid. In the latter case, however, the acid will be converted into the corresponding metal salt.

The data set forth in the following table illustrates the wetting properties of representative examples of the herein described compound in a mercerizing solution.

The method used to determine the wetting properties of these compounds is called the "String method" and is carried out by placing a bundle of 16/2" pieces of string on the surface of the mercerizing bath and noting the time required for this bundle of string to become completely wet, that is, to sink below the surface of the solution.

TABLE I

Wetting test—String method

55	Test	Material	Wetting time in seconds of 1% solution of the "material" in an aqueous 20% NaOH solution	Hours
60	1	Control		18
	2	N-n-butyl o-aminobiphenyl di-sodium-sulfonate		34
	3	N-n-propyl o-aminobiphenyl di-sodium-sulfonate		62
	4	N-n-amyl o-aminobiphenyl di-sodium-sulfonate		64
65	5	N-tertiary butyl o-aminobiphenyl di-sodium-sulfonate		82
	6	N-tertiary amyl o-aminobiphenyl di-sodium-sulfonate		60
	7	N-di-n-butylaniline di-sodium-sulfonate		45
	8	N-octyl o-aminobiphenyl di-sodium-sulfonate		246
70	9	N-dimethyl aniline monosodium sulfonate		48

It is apparent from the above data that the herein described class of di-sulfonated products are particularly effective as wetting agent in strong alkaline solutions. By comparing the data set forth in tests 8 and 9 with the data set

forth in connection with tests 1 to 7, inclusive, the unique wetting properties of the herein described class of compounds, in strong alkali solution, will be apparent.

The improved wetting and penetrating power of strong alkaline solutions containing the herein-described type of N-alkylated aryl amines disulfonates may be further demonstrated by data showing the speed of mercerization effected by a mercerizing bath containing a compound of the above type. These tests were made by suspending a weighted, single-strand of yarn in a bath of the improved mercerizing solution and observing the amount of shrinkage at 15 second intervals. The apparatus consisted of a 50 ml. burette whose graduations cover a length of 56.5 centimeters, a metal guide to center and hold the yarn and a 2 gram stainless steel weight fitted with a hook. In making the test, the burette is filled with the mercerizing solution containing the new wetting agent (1% solution by weight of the wetting agent in an aqueous 20% sodium hydroxide solution). The temperature of the solution is adjusted to 20° C. The end of a single strand of yarn (70/2 soft, cream Himalaya cotton) is attached to the 2 gram weight and the strand is then suspended in the burette with the top of the weight standing at the 50 mm. mark. The shrinkage of the yarn is noted at 15 second intervals.

Since the treatment of cotton fibers with strong alkaline solutions such as a strong aqueous solution of sodium hydroxide causes a shrinkage of the fiber, the amount of this shrinkage in a given period of time represents the efficiency or effectiveness of the mercerizing bath. By placing the strand of yarn in the above burette which contains the mercerizing agent, the efficiency of the bath can be ascertained by noting the height to which the weight rises in a given period of time. The following data obtained by the above test illustrate the efficiency of representative examples of the herein described N-alkylated aryl amine di-sulfonates when incorporated in a mercerizing bath.

TABLE II

Seconds	Percent shrinkage in aqueous 20% NaOH	Percent shrinkage in aqueous 20% NaOH containing 1% of an N-alkyl o-aminobiphenyl di-sodium sulfonates in which the alkyl radical is—			
		n-Propyl	n-Butyl	n-Amyl	Tert. amy1
30.....	0.8	12.8	13.1	13.4	12.6
45.....	1.3	13.0	13.0	13.4	12.6
60.....	1.5	12.9	12.8	13.3	12.5
120.....	3.5	13.3	13.0	13.4	12.6
240.....	5.3	13.5	13.3	13.6	12.9

The mercerizing efficiency of an aqueous 20% sodium hydroxide solution containing one per cent. of one of the above N-alkyl ortho-amino-biphenyl di-sodium-sulfonates as compared to the aqueous 20% sodium hydroxide solution alone is clearly demonstrated by the above data. In 30 seconds the sodium hydroxide solution alone caused less than 1% shrinkage in the length of the strand, whereas the mercerizing bath containing one of the above mentioned wetting agents produced a shrinkage of about 13% in the same time interval. Even after 240 seconds, the mercerizing bath without the wetting agent produced only a 5.3% shrinkage. In addition, the mercerization effected by the herein described products is uniform and the fabric can be dyed

evenly. These improvements may be accomplished with cellulosic fibers that have not been subjected to the "boiling out" or cleansing process that is normally used to remove waxes and greases from the fibers before passing them to the mercerizing bath. By using the improved mercerizing bath herein described, I not only shorten the time normally used to mercerize cellulosic fibers but I can eliminate some of the preliminary cleaning steps that are normally applied to the fibers before passing them to the mercerizing bath.

The herein described alkaline aqueous media may be employed in admixture with other addition agents for example alcohols such as secondary-amyl alcohol and tertiarybutyl alcohol; phenols such as cresylic acid; Turkey red oils and the like.

While the described invention is preferably employed in the mercerization of cotton fibers, fabrics and yarns it may be used in any art or process where it is desirable to have a strong alkaline medium having wetting, penetrating and dispersing properties.

As illustrated by the foregoing data, the herein described classes of water-soluble N-alkylated aromatic amine di-sulfonates are characterized by their high degree of wetting, penetrating and dispersing properties in alkaline solutions such as strong aqueous solutions of sodium hydroxide. These properties of the foregoing di-sulfonated products make it possible to obtain rapid and uniform mercerization, thereby effecting a substantial economy in the continuous type of mercerizing process.

Inasmuch as the above specification comprises preferred embodiments of the invention, it is to be understood that the invention is not limited thereto and that variations and changes may be made without departing substantially from the invention as defined in the appended claims.

I claim:

1. An alkaline mercerizing solution containing as a wetting agent an N-alkylated aromatic amine di-sulfonate having the following general formula:

50 wherein R represents an aromatic radical selected from the group consisting of benzene, biphenyl and naphthalene radicals, R₁ represents a hydrogen or an alkyl radical containing from two to six carbon atoms, Me represents an alkali metal, and the term "alkyl" represents an alkyl radical containing from two to six carbon atoms.

55 2. A strongly alkaline medium of improved wetting properties comprising an aqueous alkali metal hydroxide solution of an N-alkylated aromatic amine di-sodium-sulfonate having the following general formula:

65 wherein R represents an aromatic radical selected from the group consisting of benzene, biphenyl and naphthalene radicals, R₁ represents a hydrogen or an alkyl radical containing from two to six carbon atoms, and the term "alkyl" represents an alkyl radical containing from two to six carbon atoms.

70 3. In the process of producing mercerized cotton materials, the step which comprises subjecting cotton fibers and fabrics to treatment with

a sodium hydroxide mercerizing bath containing as a wetting agent a small amount of a water-soluble N-alkylated aromatic amine di-sulfonate having the following general formula:

wherein R represents an aromatic radical selected from the group consisting of benzene, biphenyl and naphthalene radicals, R₁ represents a hydrogen or an alkyl radical containing from two to six carbon atoms, Me represents an alkali metal, and the term "alkyl" represents an alkyl radical containing from two to six carbon atoms.

4. A strongly alkaline medium of improved wetting properties comprising an aqueous alkali metal hydroxide solution of mercerizing strength, characterized by containing an N-alkylated aromatic amine di-sulfonic having the following general formula:

wherein R represents a biphenyl radical, R₁ represents a hydrogen or an alkyl radical containing from two to six carbon atoms, Me represents an alkali metal, and the term "alkyl" represents an alkyl radical containing from two to six carbon atoms.

5. An alkaline mercerizing solution containing as a wetting agent an N-alkylated aromatic amine di-sulfonate having the following general formula:

wherein R represents a biphenyl radical, R₁ repre-

sents a hydrogen or an alkyl radical containing from two to six carbon atoms, Me represents an alkali metal, and the term "alkyl" represents an alkyl radical containing from two to six carbon atoms.

6. A wetting agent capable of increasing the wetting properties of aqueous solutions of alkali metal hydroxides, which comprises an N-alkyl ortho-amino biphenyl disulfonate wherein the alkyl group contains from two to six carbon atoms.

10 7. A new composition of matter comprising an N-alkylated biphenylamine disulfonate having the general formula:

wherein R represents a biphenyl radical, R₁ represents a hydrogen or an alkyl radical containing from two to six carbon atoms, Me represents an alkali metal, and the term "alkyl" represents an alkyl radical containing from two to six carbon atoms, said compounds being soluble in aqueous alkaline solutions and possessing wetting properties.

25 8. A new composition of matter comprising an N-dialkylated biphenylamine disulfonate having the following general formula:

wherein R represents a biphenyl radical, R₁ and R₂ represent butyl radicals and Me represents an alkali metal, said compounds being soluble in aqueous alkaline solutions and possessing wetting properties.

ROBERT L. SIBLEY.

CERTIFICATE OF CORRECTION.

Patent No. 2,245,162.

June 10, 1941.

ROBERT L. SIBLEY.

It is hereby certified that error appears in the printed specification of the above numbered patent requiring correction as follows: Page 1, first column, line 40, in the equation, for "R₂" read --R₁--; page 2, first column, line 53-54, for "constituents" read --constituents--; and second column, line 13, for "solfonation" read --sulfonation--; line 26, for "or" read --of--; line 44, for "boundle" read --bundle--; and that the said Letters Patent should be read with this correction therein that the same may conform to the record of the case in the Patent Office.

Signed and sealed this 15th day of July, A. D. 1941.

(Seal)

Henry Van Arsdale,
Acting Commissioner of Patents.
